PRODUCT DISPLAY TRAY

Kenneth M. Kenmotsu, Morton Grove, Ill., assignor to Chicago Display Company, Melrose, Park, Ill.

Filed Apr. 21, 1970, Ser. No. 22,541

Term of patent 14 years

Int. Cl. D6—06

U.S. Cl. D80—9

FIG. 1 is a front perspective view of a product display tray showing my new design;

FIG. 2 is a rear perspective view thereof;

FIG. 3 is a bottom perspective view thereof; and

FIG. 4 is another front perspective view thereof, a second tray being illustrated and broken lines to indicate the interfitting relationship between two trays.

I claim:

The ornamental design for a product display tray, as shown and described.
